UNITED STATES PATENT OFFICE

WILLARD F. RICHARDS, OF DEPEW, NEW YORK, ASSIGNOR TO THE SYMINGTON COMPANY, OF NEW YORK, N. Y., A CORPORATION OF MARYLAND

HAND BRAKE

Application filed June 13, 1928. Serial No. 285,059.

This invention relates to hand brakes and more particularly to a geared brake in which the chain winding drum and main gear are mounted about vertical pivotal means.

The particular object of my invention, generally considered, is to provide a geared hand brake having a vertical chain winding drum, providing quick initial take-up by means of an arm thereon with a main internal gear 5 associated from said drum but associated for movement in unison therewith, a lug for that purpose extending from one of said members and received in a socket in the other, said main gear being driven by a vertical pinion formed with an extended hub portion rotatable 10 mounted in the base casting and formed with an upwardly opening socket for receiving a brake staff or other actuating means.

Another object of my invention is to provide brake mechanism involving a vertical winding drum with a main gear preferably non-integral therewith but moving in unison on account of interlocking means therebetween, said gear being driven by a pinion provided with an upwardly extended hub portion entered from below into a corresponding aperture in the base casting, means being provided connected to the lower face of said casting and underlying said pinion for holding it in place or said pinion hub may be held 20 in a split bearing bushing retained in place in a corresponding aperture in the base casting.

A further object of my invention is to provide brake mechanism involving a base casting formed with a depending bracket between which and the casting is mounted an upright pivot pin, said pin being freely received in the casting at its upper end and held 30 in position at its lower end by a flat key passed through a slot in the pin and a specially formed slot in the bottom of the bracket, providing means for driving out the pin when necessary, a brake chain winding drum and 35 associated main internal gear mounted on said pin and interlocked with respect to each other for movement together, a driving pinion meshing with said main gear and formed with an upwardly extending bearing hub rotatably received in said base casting, said

pinion and hub portion being held in place by a bottom bearing bracket connected to the lower face of the casting between said casting and main gear and formed with a spud fitting in the lower end of said pinion for holding it 55 in place while permitting rotation thereof.

Other objects and advantages of the invention relating to the particular arrangement and construction of the various parts will become apparent as the description proceeds.

Referring to the drawings illustrating my invention, the scope whereof is defined by the appended claims:

Figure 1 is a plan of one embodiment of my 60 brake mechanism.

Figure 2 is a vertical sectional view on the line 2—2 of Figure 1, looking in the direction of the arrows.

Figure 3 is a horizontal sectional view on the line 3—3 of Figure 2, looking in the direction of the arrows.

Figure 4 is a fragmentary elevational view of the lower end of the brake chain winding drum and supporting bracket therefor, looking from a direction at right angles to that of Figure 2.

Figure 5 is a horizontal sectional view on the line 5—5 of Figure 2, looking in the direction of the arrows.

Figure 6 is a plan corresponding to Figure 1 but showing a modification.

Figure 7 is a vertical sectional view on the line 7—7 of Figure 6, looking in the direction of the arrows.

Figure 8 is a horizontal sectional view on the line 8—8 of Figure 7, looking in the direction of the arrows.

Figure 9 is a vertical sectional view on the line 9—9 of Figure 6.

Referring to the drawings in detail, like parts being designated by like reference characters, and first considering the embodiment of my invention illustrated in Figures 1—5, inclusive, there is shown hand brake mechanism 90 comprising a base or bracket casting 2 connected to the end of a railway vehicle 3 in any desired manner, as by means of rivets 4 and 5 extending through, respectively, the horizontal and vertical flange of the end sill 6 of the vehicle or car and the adjacent web or flange 95 100

portions 7 and 8, respectively, of the base casting 2. Said base casting has the edge of its main web or floor 7 rigidified by beading 9 which, at the outer end portion, is enlarged to form the depending strengthening flange 10 and at its side portions is further extended to form a depending bracket or loop portion 11 which extends downwardly from either side of the main web or floor 7 of the casting and is connected by a horizontal brake chain winding drum supporting portion 12. The sides of said bracket portion 11 gradually taper or decrease in strength and width from the base web 7 to the connecting portion 12.

Mounted between the web 7 of the base casting 2 and the connecting portion 12 of the bracket 11 thereof is a pin 13, the upper end of which is freely received in a corresponding aperture 14 and the lower end of which is likewise received in an aperture 15 in the supporting portion 12 of the bracket 11. The lower end of said pin 13 is immovably held in the supporting portion 12 of the bracket portion 11 by means of a preferably flat key 16, which passes through corresponding apertures 17 and 18 in the pin and supporting portion 12, respectively. In order to facilitate insertion and removal of the key 16 when necessary, one of said apertures 18 is preferably enlarged to form a specially constructed slot, as shown most clearly in Figure 4, which permits the insertion and removal of the pin 13 when the key 16 is only partly withdrawn therefrom. From a consideration of the drawings it will be clear that in order to insert the pin 13 in place the key 16 may be applied so that it extends from one end only of the slot or aperture 17 in the pin, which extending end is then receivable in the lower portion 19 of the enlarged slot 18, the other end of said key 16 not extending beyond the aperture 17 and not interfering with its passage to register with the opening 18. After the extended end of the key has passed above the ledge portion 20 which makes the extended slot 18 L-shaped in side elevation, the pin 13 is turned so that the key 16 overlies said ledge portion 20 and retains the pin 13 temporarily in place. When this has been accomplished the other end of the key registers with the other opening 18 and said key may be driven through said opening and the end turned to prevent undesired removal thereof, as indicated most clearly in Figure 5. In order to remove the pin 13 the process is reversed, the end of the key 16 adjacent the hole 18 being straightened out and driven out until it is flush with the corresponding end of the hole 17 in the pin 13, whereupon said pin 60 may be rotated until the extending end of the key 16 registers with the vertical or open portion of the notch 18 so that said pin may be readily withdrawn.

Rotatably mounted on the pin 13 is the chain winding drum 21 and the associated

main gear 22, said main gear being preferably of the internal type and formed separate from the drum 21, although it will be understood that, if desired, it may be formed integral therewith. In the present embodiment the drum 21 is of volute form and provided with an arm or portion of maximum radius 23 to which the brake chain (not shown) is connected, as by means of a pin (not shown) passing through registering apertures 24. Upon turning of the drum 21 the chain is wound up at a decreasing rate, as will be understood. The upper end of said drum is formed with a non-circular pocket or notch 25 receiving a correspondingly formed lug 26 extending from the bottom face of the internal gear 22. Said lug and socket portions are desirably formed elongated with opposite parallel faces, as shown most clearly in Figure 3, whereby said elements are adapted to move in unison and force is efficiently transmitted from the gear 22 to the drum 21, as will be understood.

For driving the gear 22 a pinion 27 is provided, said pinion being desirably entered from below in the web 7 of the base casting 2 and for that purpose being provided with an extended hub portion 28 rotatably received in the aperture 29 in the casting 2, said apertured portion being strengthened by an upstanding cylindrical flange portion 30 forming a bearing for the hub 28 of the pinion 27. Said flange portion 30 is desirably connected to the upstanding flange 8 of the casting by webs 31 which rigidify both the flanges 8 and 30, said flange 8 being preferably additionally rigidified by triangular gusset portions 32 on opposite sides of the webs 31. The hub portion 28 of the pinion 27 is formed with an upwardly opening non-circular socket or pocket 33 adapted to receive the lower end of a brake staff or other actuating means (not shown). Said actuating means may be connected to the pinion 27 by cotter or other connecting means extending through the registering apertures 34 in the hub portion 28 and the lower end of the brake staff.

For holding the pinion 27 in place and preventing it dropping after assembly with the base casting 2, a bottom bearing bracket 35 is provided and formed with an aperture receiving the depending boss 36 around the opening 14 for the upper end of the pin 13 and preferably apertured, as indicated at 37, to receive a depending boss 38 of corresponding size, whereby when said bracket is assembled with the base casting it is also held in the desired angular position with respect thereto without relying on the connecting rivet 39 for that purpose. Said bearing bracket 35 is formed with a spud or trunnion portion 40 which is preferably tapered, as illustrated particularly in Figure 2, and fits in a corresponding aperture in the pinion 130

27, thereby providing, in effect, a lower thrust bearing for said trunnion and holding it in proper relation with respect to the casting 2 and gear 22. In order to prevent undesired upward movement of the pinion 27 a collar or annular flange portion 41 is preferably provided thereon.

5 Referring now to the embodiment of my invention illustrated in Figures 6-9, inclusive, a construction is there disclosed in which a base or bracket casting 2^a is provided with depending bracket portions 11^a connected by a lower horizontal portion 12^a which supports the lower end of the pin 13^a as in the previous embodiment. Said pin 13^a, however, is shown unrestrained from rotary movement in that a supporting cotter 16^a underlies the lower end of said pin rather than extending through the same as in the 20 previous embodiment.

The brake chain winding drum 21^a is, as in the previous embodiment, preferably formed separate from the internal main gear 22^a and said members are connected for simultaneous rotation by the lug portion 26^a extending from the lower face of the main gear 22^a, as in the previous embodiment. In the present embodiment, the hub of the lug portion is extended beyond the lug 26^a as a 25 frusto-conical centering projection telescoping in the hub of the winding drum 21^a.

The upper end of the pin 13^a is received in a pocket formed by a depending cylindrical flange 36^a, which, in the present embodiment, lies beneath the upstanding flange 8^a of the base casting 2^a. The web or floor 7^a of the base casting 2^a may be lightened as in the previous embodiment by a plurality of apertures 42, as illustrated.

40 In the present embodiment the pinion 27^a may be entered from above the web 7^a of the base casting and therefore it is unnecessary to provide a bracket corresponding to the bottom bearing bracket 35 of the previous embodiment. Said pinion 27^a in the present embodiment, however, is formed with an extended hub portion 28^a preferably provided with spaced annular collars 41^a leaving a bearing or journal portion 43 therebetween. Surrounding said bearing portion 43 is a pair 45 of bearing blocks 44 formed with outstanding lugs 45 at their ends which serve for connecting them in the bearing pocket 30^a, as by rivets or other connecting means 46 extending through said lug portions 45 and the adjacent walls of the pocket 30^a. The curved sides of the bearing blocks 45 are preferably tapered, as indicated at 47 in Figure 9, to provide a good fit for said blocks in the pocket portion 30^a. As in the previous embodiment, the bearing pocket 30^a is connected to the upstanding flange 8^a by a web or flange 31^a and said flange 8^a is desirably reinforced by triangular gusset portions 32^a spaced on either side of the web portion 31^a. As in the

previous embodiment the hub portion 28^a of the pinion 27^a is formed with a non-circular preferably substantially square pocket 33^a for receiving the lower end of actuating means, such as a brake staff (not shown). Except as specifically described in connection with the present embodiment the same may correspond with that of the first embodiment.

70 From the foregoing description, taken in connection with the accompanying drawings, it will be seen that I have devised hand brake mechanism in which a base or bracket casting is provided and formed with a depending loop serving to mount the lower end of the winding drum pivot pin, said pivot pin supporting not only the drum but the main gear which is preferably internal and non-integral therewith. The drum and main gear are adapted to move in unison by the provision of a lug on one of the members extending into a corresponding pocket in the other, providing an interlock therebetween. The main gear is desirably driven by a pinion with an upwardly extended hub portion pocketed to 75 receive the lower end of the brake staff or other actuating means. Said pinion may be entered from below and held in place by a bottom bearing bracket with a spud inserted in the end of said pinion or by a split bushing or bearing block held in place in the base casting. The pin upon which is rotatably mounted the main gear and brake chain winding drum may be either supported without being prevented from rotating or may be held in position and prevented from rotation by a flat key passed through a slot in the lower end of the pin and a specially formed slot in the bottom of the housing whereby 80 said pin may be readily inserted and removed 85 as such becomes necessary.

90 Having thus described my invention, I claim:

1. Brake mechanism comprising a casting with a depending bracket portion, a pin between said casting and bracket portion, a winding drum rotatably mounted on said pin, a main gear on said pin, means for causing said gear and drum to move in unison, a pinion meshing with said gear, a bearing portion integral with said pinion, said casting being formed with an aperture receiving said bearing portion of the pinion when entered from below, and a bottom bearing bracket for said pinion extending therebeneath.

110 2. Brake mechanism comprising a base casting, a bracket portion depending therefrom, a brake chain winding drum and main gear rotatably mounted between said casting and bracket portion, a pinion meshing with said main gear, an integral hub portion on said pinion extending upwardly into and rotatably received in said base casting, and a bottom bearing bracket for said pinion connected to the lower face of said casting and 115 120 125 130

formed with a supporting spud extending into the end of the pinion.

3. Brake mechanism comprising a casting with a depending bracket portion, a pin between said casting and bracket portion, a winding drum and gear rotatably mounted on said pin, a pinion meshing with said gear, a bearing portion integral with said pinion, said casting being formed with an aperture receiving said bearing portion of the pinion when entered from below, and a bottom bearing bracket for said pinion extending between said casting and gear.

4. Brake mechanism comprising a base casting, a brake chain winding drum and main gear rotatably mounted in said casting, a pinion meshing with said main gear, and integral hub portion on said pinion extending upwardly into and rotatably received in said base casting, and a bottom bearing bracket for said pinion connected to the lower face of said casting above the gear and formed with a supporting spud extending into the end of the pinion.

5. Brake mechanism comprising a base casting formed with a depending bracket portion, a pin extending between said casting and bracket portion, a key passing through the lower end of said pin and through slots in said bracket portion, and a winding drum and main gear rotatably mounted on said pin, the slots in the bracket portion being so formed that the pin may be removed upon partial removal only of the key therefrom and rotation of the pin.

In testimony whereof I affix my signature.

WILLARD F. RICHARDS.
